R. B. GRIFFITH.

COPY HOLDER.

APPLICATION FILED JAN. 15, 1912.

1,120,192.

Patented Dec. 8, 1914

UNITED STATES PATENT OFFICE.

RUSSELL B. GRIFFITH, OF ROCHESTER, NEW YORK, ASSIGNEE, BY MESNE ASSIGNMENTS, TO LINEATIME MANUFACTURING CO., INC., OF ROCHESTER, NEW YORK.

COPY-HOLDER.

1,120,192.

Specification of Letters Patent.

Patented Dec. 8, 1914.

Original application filed January 6, 1908. Serial No. 409,550. Divided and this application filed January 15, 1912. Serial No. 671,191.

To all whom it may concern:

Be it known that I, RUSSELL B. GRIFFITH, of Rochester, in the county of Monroe and State of New York, have invented certain new and useful Improvements in Copy Holders; and I do hereby declare the following to be a full, clear, and exact description of the same, reference being had to the accompanying drawings, forming a part of this specification, and to the reference-numerals marked thereon.

My present invention relates to copy-holders or paper holders, and it has for its object to provide a copyplate or pad supporting backing with simple and cheaply constructed though efficient and convenient means for temporarily holding a sheet or a plurality of sheets of paper in place thereon for the purpose, for instance, of reading or transcribing the writing they contain.

A further object of the invention is to also provide means for holding the turned pages back and the improvements are particularly adapted for line indicating or movable copyholders of the character set forth in my prior application Serial No. 409,550, filed January 6, 1908, of which this application is a division.

To these and other ends, the invention consists in certain improvements and combinations of parts all as will be hereinafter more fully described, the novel features being pointed out in the claims at the end of the specification.

In the drawings: Figure 1 is a perspective view of a line indicating copyholder embodying a copyplate constructed in accordance with and illustrating one embodiment of my invention; Fig. 2 is a rear elevation of a portion of the upper part of the copyplate showing the manner in which the paper clips are journaled thereon and the springs for actuating them; Fig. 3 is a side elevation of the parts shown in Fig. 2 with the clips in released position, and Fig. 4 is a view similar to Fig. 3 with the clips in normal or gripping position.

Similar reference numerals throughout the several figures indicate the same parts.

As above indicated, my improvements are particularly useful in connection with line indicating mechanical copyholders and in

Fig. 1 is shown such a copyholder, which, described generally, comprises a frame A provided with suitable guides on which slides vertically a vertically disposed and preferably flat copyplate or backing 1. A stationary line indicator B spans the face of the plate and the copy, held to the latter in the manner hereinafter described, is moved past the indicator with a step-by-step movement communicated to the plate through suitable intermediary devices connected with an operating lever C extending forwardly from the frame and plate. When the latter has been elevated to a point at which the bottom line is carried past the indicator B, the plate is released and dropped back to its original position in order that the indicator may traverse the next page in the same manner, and before or after the release, the copied page is turned to reveal the next, all as set forth in the prior application referred to.

In the practice of my present invention, the copyplate 1 is preferably formed of thin sheet material and rectangular in outline, its dimensions approximating the maximum dimensions of the copy sheets which it is designed to accommodate and at one end, in the present illustrated embodiment, the upper end, is arranged the main copy-holding clip for receiving the sheets against the face of the plate. This clip may be conveniently constructed from a single piece of material, such as wire and comprises in the present instance a yoke having a bar portion 2 disposed across the face of the copy plate and having a looped portion 3 at one end, preferably, both ends, the material beyond the loops extending at right angles to the bar and again looped at 4 and thence inwardly at 5 parallel with the bar, the inwardly extending portions being pivoted in brackets 6 secured to the rear of the copy plate. A spring or tension member 7 normally operates to press the bar 2 against the face of the copy plate, while the looped portions 3 are bent outwardly angularly to the general plane of the clip as shown in Figs. 2 and 3 to form a better purchase for the fingers of the operator in raising the bar upon an axis transverse to the copy plate against the tension of the spring to insert the copy.

Arranged above the copy retaining clip just described is a leaf retaining clip 8 which I prefer to construct in a similar manner, with the exception that an inner loop corresponding to the loop 4 may be dispensed with. It is also pivoted in the bracket 6 to move upon an axis parallel with that of the other, but is fitted with a tension member 9 which normally presses it against the face of the copy plate in an opposite direction. It also being provided with an angularly disposed loop 10, it will be seen that both clips may be released and moved toward one another by pressing the loops together. In this way, the copy may be quickly removed from the holder and the action of both clips, or both may be raised and an open copy book inserted in such manner that they will simultaneously engage, one with the page to be copied and the other with those turned back. In either instance, the strain upon the copy plate is slight, as the two clips work against each other. As each page is copied, it is turned back on the bar 2 and slipped beneath the leaf retaining clip by lifting the latter through outward pressure on the finger piece. To obtain a greater range of movement for both clips, and to make it conform more nearly to the naturally assumed position of the folded leaves, I prefer to bend or incline the upper end of the copy plate rearwardly, as shown at 11. The brackets 6 are preferably disposed across the line of demarcation 12 and their fastening 13 arranged upon both sides thereof for strengthening purposes.

While, as I have stated, the present invention is particularly applicable to copy holders of the type illustrated, it is plain that it is not limited to such use as, for instance, the plate 1 might be an ordinary writing board such as is used to hold a writing pad, but the functions of the clips 45 in holding the latter and its turned pages in place would be the same.

I claim as my invention:

1. In a copy holder, the combination with a copy plate, of a spring actuated copy retaining clip mounted to turn about an axis extending transversely of the clip, and having an operating portion, and a spring actuated leaf retaining clip mounted to turn about a horizontal axis and having an operating portion located in proximity to the operating portion of the copy retaining clip, said clips having a normal tendency to rotate in opposite directions.

2. In a copy holder, the combination with a copy plate, of a copy retaining clip comprising a bar extending transversely across the face of the copy plate and having a looped portion at each end arranged at the sides of the latter, the material beyond the loops extending at right angles to the bar

and again looped and thence inwardly parallel with the bar, the inwardly extending portions being pivoted to the copy plate and said first mentioned looped portions being bent angularly to the general plane of the clip and to the plane of the last mentioned loop, and a tension member normally operating to press the bar against the face of the copy plate.

3. In a copy holder, the combination with a copy plate, of a copy retaining clip pivoted thereto comprising a bar extending across the face of the copy plate and movable toward and from the latter upon an axis disposed transversely thereto, a similarly formed leaf retaining clip arranged above the other, the axes of said clips being parallel, and tension members normally operating to force the bars of both clips in opposite directions against the face of the copy plate.

4. In a copy holder, the combination with a copy plate, of a copy holding clip comprising a yoke having a central bar portion extending across the face of the copy plate and its ends pivoted to the latter to render said bar movable toward and from the copy plate on an axis extending transversely thereof, a similarly formed leaf retaining clip arranged above said copy holding clip, the axes of the clips being parallel, and tension members normally operating to force the bar portions of both of said clips in opposite directions against the face of the copy plate.

5. In a copy holder, the combination with a copy plate having a rearwardly extending portion at its upper end, of a copy holding clip pivoted thereto comprising a bar extending across the face of the copy plate below the rearwardly extending portion and movable toward and from the face of the copy plate on an axis disposed transversely thereto, a similarly formed leaf retaining clip arranged above said copy holding clip and having its bar portion extending across the rearwardly extending portion of the copy plate and tension members normally operating to force the bar portions of both clips in opposite directions against the copy plate.

6. In a copy holder, the combination with a copy plate, of a copy retaining clip pivoted thereto comprising a bar extending across the face of the copy plate and movable toward and from the latter upon an axis disposed transversely thereto, said bar being provided at one end with a portion extending angularly to the plane of the clip, a similarly formed leaf retaining clip arranged above the other, the axes of said clips being parallel, and tension members normally operating to force the bars of both clips in opposite directions against the face of the copy plate, the angularly extending

portions of the two clips constituting gripping points offset to the same side of the plane of the axes of the clips.

7. In a copy holder, the combination with
a copy plate, of a spring actuated copy retaining clip mounted to turn about an axis extending transversely of the clip, and having an operating portion, and a spring actuated leaf retaining clip mounted to turn about a horizontal axis and having an oper-
- ating portion located in proximity to the operating portion of the copy retaining clip, said clips having a normal tendency to rotate in opposite directions, and a portion of each clip being extended beyond the axis of 15 the other.

RUSSELL B. GRIFFITH.
